E. WHALLEY

JACK

Filed March 16, 1922

FIG. 1.

FIG. 2.

Enoch Whalley, INVENTOR.

BY

Frank A. Cutter, ATTORNEY.

UNITED STATES PATENT OFFICE.

ENOCH WHALLEY, OF WILLIMANSETT, MASSACHUSETTS.

JACK.

Aplication filed March 16, 1922. Serial No. 544,175.

To all whom it may concern:

Be it known that I, ENOCH WHALLEY, a citizen of the United States of America, and a resident of Willimansett, in the county of Hampden and State of Massachusetts; have invented a new and useful Jack, of which the following is a specification.

My invention relates to improvements in devices or implements that are especially adapted for pulling or drawing purposes, and resides in a suitable casing or body equipped with holding and releasing and operating means for a rotary toothed element or elements, in a rack-provided drawing bar and toothed means for operating the same, and in means for disengaging the holding means or element from the toothed member engaged thereby, together with such other parts and members as may be necessary or desirable in order to render the implement complete in every respect, all as hereinafter set forth.

The primary object of my invention is to produce an implement of the character described which is strong and durable, and consists of few parts, can be operated conveniently and expeditiously. This implement is more especially designed for use in a horizontal position for traction purposes, as when an automobile becomes stalled in a ditch, mud hole, or other place from which it cannot be propelled by its own power, or in a vertical position for raising a heavy object or objects, and holding the same suspended if desired.

A further object is to provide the jack with a simple but adequate means of control for the toothed members.

Other objects and advantages will appear in the course of the following description.

I attain the objects and secure the advantages of my invention by the means illustrated in the accompanying drawings, in which—

Figure 1 is a side elevation of a jack which embodies a practical form of my invention, and, Fig. 2, a side elevation, with parts broken away, of said jack.

Similar reference characters designate similar parts throughout the several views.

This jack may be used in either a horizontal or a vertical position, and is designed to have ropes or chains attached to op-

posite ends thereof, and the same comprises a body 31, at one end of which is an integral hook 32; a draft or traction bar 33 having at one end an integral hook 34, and provided with teeth 35 which form a rack, such bar being arranged to slide in said body; a gear 36 mounted on a spindle 37 carried by said body, said gear intermeshing with said rack; a pawl 38 pivoted at 39 to said body, and normally held in engagement with said gear by a spring 40 attached at opposite ends to the body and pawl; a handle 41 bifurcated to provide arms 42 which are mounted on the outer terminals of said spindle; a latch 43 located in a recess 44 in said handle, and having an arm 45 that extends through a slot 46 in the handle; a rod 47 passing through said last-named arm, and through a lug 48 on the underside of the handle; a spring 49 on said rod between said latch arm and said lug; a cord 50 extending from said rod to and through a second lug 48 on the underside of the handle, and having a ring 51 at the forward end; and a bow spring that forms a trip 52 for said pawl, said trip having its base secured at 53 to one of the handle arms. A longitudinally-movable pin 54 is provided in the pawl 38.

The slip pin 54, which extends laterally through the pawl 38, may be positioned either in or out of the path of the trip 52, by pushing said pin out over the arm 42 upon which said trip is mounted, or by pushing said pin in the opposite direction until it is clear of the trip or out of said path. The trip 52 curves upwardly and rearwardly from its base.

After suitable connections or attachments have been made with or to the hooks 32 and 34, the operation of the jack is as follows:

The latch 43 is withdrawn from the gear 36, the handle 41 is rocked upwardly to permit said latch to be engaged with a new or fresh tooth of said gear and the latch is released for such engagement, and said handle is forced downwardly again. This action partially rotates the gear 36 and causes the bar 33 to be actuated to the left, or the body 31 to the right, or in any event the distance between the hooks 32 and 34 is decreased. At the same time the pawl 38 is rocked by the gear 36 on the pivot 39, against

the resiliency of the spring 40, and snaps into engagement with a newly presented tooth of said gear. The gear is now held by the pawl against the force of the load, and all is in readiness for a repetition of the drawing action of the jack. Such action is repeated as many times as may be necessary. During these operations the pin 54 is in its retracted position, but when it is desired to release the rod, said pin is thrust into the path of the trip 52, while the handle is in elevated position and with the latch retracted. The trip 52 is now in the position represented by broken lines in Fig. 2. Next the handle is thrust downwardly, with the latch still in retracted position, until the trip contacts with the pin 54 and forces the same upwardly, and with it the pawl. The pawl is rocked upwardly far enough, by the aforesaid action, to cause said pawl to clear the gear 36. This releases the parts and members holding the rod, and so releases the latter.

The body 31 may be provided with supporting and steadyng flanges, as 55—55, on the normal bottom thereof.

More or less change in matters of shape, size, construction, and arrangement of some or all of the parts of my implement, may be made without departing from the nature of my invention, or exceeding the scope of what is claimed.

What I claim as my invention, and desire to secure by Letters Patent, is—

1. The combination, in a jack of the class described, with a body provided with a spindle, and with attaching means for a chain or rope, a rack bar reciprocable in said body, and also provided with attaching means for a chain or rope, said two attaching means being at relatively opposite ends of said body and bar, a gear mounted on said spindle and intermeshing with the teeth on said bar, and a pawl pivotally connected with said body, and adapted to engage said gear, said pawl having a pin projecting therefrom, of a handle also mounted on said spindle, and equipped with a latch to engage

said gear, and further equipped with a trip to contact with said pin.

2. The combination, in a jack of the class described, with a body provided with a spindle, and with attaching means for a chain or rope, a rack bar reciprocable in said body, and also provided with attaching means for a chain or rope, said two attaching means being at relatively opposite ends of said body and bar, a gear mounted on said spindle and intermeshing with the teeth on said bar, a pawl pivotally connected with said body to engage said gear, and a slip pin carried by said pawl, of a handle also mounted on said spindle, and equipped with a latch to engage said gear, and a trip mounted on said handle, and into the path of which said pin may be projected, said trip being adapted, when said pin is in the path thereof and the handle is rocked, to act on the pin and operate said pawl.

3. The combination, in a jack of the class described, with a body provided with a spindle, and with attaching means for a chain or rope, a rack bar reciprocable in said body, and also provided with attaching means for a chain or rope, said two attaching means being at relatively opposite ends of said body and bar, a gear mounted on said spindle and intermeshing with the teeth on said bar, a pawl pivotally connected with said body, and adapted to engage said gear, and a slip pin carried by said pawl, of a handle also mounted on said spindle, a spring-bressed latch carried by said handle to engage said gear, means also carried by the handle to retract said latch, and a trip mounted on said handle in position to contact with said pin, when it is in the path thereof, and actuate said pawl out of engagement with said gear, through the medium of said pin, when said handle is rocked downwardly.

ENOCH WHALLEY.
